PALLETIZED DISPENSING CONTAINER

Larry J. Budd, Chicago, James G. Heidenreich, Des Plaines, Richard J. Lane, Wilmette, and Howard G. Haffenber, Chicago, Ill., assignors to Pallet Devices, Incorporated, Des Plaines, Ill., a corporation of Illinois

Application April 18, 1950, Serial No. 156,571

9 Claims. (Cl. 229—7)

The present invention relates to a palletized dispensing container, and more particularly, to a container for the dispensing of flowable material and having a multi-thickness bottom carrying thereon means for spacing the bottom from a supporting surface, thereby facilitating handling of the container.

In the materials handling art, the handling of flowable materials has long presented a problem. The desirability of employing lift trucks for the movement of palletized loads has long been appreciated, but the difficulty of dispensing flowable materials from a container supported on a pallet has remained a problem. The present invention now provides a novel means for packing and handling such material, so as to utilize the handling advantages and economies of lift truck operation.

The container of the present invention is provided with attached legs which serve to space the container above a supporting surface while at the same time eliminating the necessity of a separate pallet. The container as a whole is made of low cost sheet material, such as paper board or the like, and the entire container-dispenser, together with its integral pallet, is susceptible to inexpensive manufacture, so that it is expendable after a single use, thereby eliminating the necessity of shipping the container and/or pallet for reuse.

In general, the container of the present invention comprises a multi-sided box having an open top and a multi-thickness bottom wall. The bottom wall carries thereon to depend therebeneath a plurality of fiber board or similar legs. Preferably, at least one of the legs is in the form of tubular stock secured to the bottom wall by portions of the bottom wall deformed from the plane thereof into the interior of the legs. The aperture thus formed in the bottom wall may be utilized for the dispensing of flowable material with the hollow leg serving as a dispensing conduit.

For uniformity and economy of manufacture, all of the supporting legs are preferably of tubular configuration, and the multi-thickness bottom wall of the present invention covers the leg apertures of certain of the legs of the container, while certain other legs communicate with the interior of the box through the bottom wall for permitting the dispensing of flowable material therefrom. Means carried by the container itself and movable relative thereto are provided for controlling material flow through the dispensing legs.

Preferably, the container of the present invention takes the form of a three-sided or triangular structure so that a pair of containers when bound together form a rectangular structure which may be readily handled in use, while the load carried by the container may be readily subdivided if desired by emptying only one of the containers.

The container of the present invention is adapted to receive and dispense flowable material generally, including granulated solids, such as lamp black, thermoplastic molding powders, vegetables, and the like; semi-solids, such as tar, viscous paints, mayonnaise, and the like; and liquids, such as solvents and the like. In the case of semi-solids and

liquids, the container is preferably provided with a fluid-tight liner and/or all container joints are made fluid-tight.

It is, therefore, an important object of the present invention to provide an improved palletized dispensing container which is provided with attached depending supporting legs.

Another important object of the present invention is to provide an improved dispensing container including a container body of paper board or the like having tubular depending legs adapted to serve as dispensing passages or conduits for materials in the container.

It is a further important object of the present invention to provide an improved dispensing container including a container body portion adapted to receive flowable material, hollow depending supporting legs, at least some of which communicate with the interior of the container, and means for controlling the flow of material from the container through the hollow legs.

It is still another important object of the present invention to provide a dispensing container including a multi-

thickness lower container wall and upstanding container side walls defining an interior space adapted to receive flowable material and communicating with the exterior through tubular supporting legs carried by the bottom wall and controlled by valve elements interposed there-

between.

A more specific object of the present invention is to provide a shipping container comprising a pair of triangular separate containers secured together to form a rectangular larger unit, each of the containers having hollow supporting legs communicating with the interior thereof to accommodate dispensing of material therefrom, each of said containers also having a slideable valve element journaled thereby for controlling communication from the container interior through the legs.

Other and further important objects of the present invention will be apparent from the disclosures in the specification and the accompanying drawings.

On the drawings:

Figure 1 is an elevational perspective view of a container of the present invention comprising a pair of assembled dispensing containers;

Figure 2 is a plan elevational view of the assembly of Figure 1;

Figure 3 is an elevational view of a blank for forming a dispensing container of the present invention;

Figure 4 is a front elevational view, with parts broken away and in section, of a dispensing container of the present invention;

Figure 5 is a sectional view taken along the plane V—V of Figure 4;

Figure 6 is a sectional view taken along the plane VI—VI of Figure 5; and

Figure 7 is a view of a blank for the container top.

As shown on the drawings:

In Figures 1 and 2, reference numeral 10 refers generally to an assembled container comprising a pair of generally triangular dispensing containers 11 bound together into an integral unit by means of flexible metal binding strips 12, as is well understood in the art.

Each of the containers 11 is formed from a blank such as that illustrated in Figure 3, the blanks being die-cut to shape and scored for folding, as is well understood in the art. The blank 13 includes a rear side panel 14, a first front side panel 15 and a second front side panel 16. The side panels 14—16 each carry a scored top flap 17 adapted to be folded along the score lines 18 during assembly of the container.

The rear side panel 14 also carries a generally triangular bottom panel 19 adapted to be folded along fold line 20 during assembly and is provided with a plurality of groups 21 of die-cut laterally spaced segmental fingers 24. A group 21 of fingers is provided at each corner of

the bottom panel 19, and in addition a group of fingers 21 is provided at the center of the side of the panel 19 adjacent the fold line 20, the group 21 at the apex of the triangle opposite the fold line 20 being relatively larger than those groups of fingers aligned adjacent the fold line 20.

Each group of segmental fingers 21 includes a central die-cut aperture 22 and die-cut separation lines 23 extending radially from the aperture 22 and cooperating therewith to define individual tabs or fingers 24. The separate fingers 24 are joined to the panel 19 by means of a peripheral score line 25 common to each of the fingers.

The front sides 15 and 16 also carry complementary bottom panels 26 and 27, respectively, joined to the sides 15 and 16 by score lines 26a and 27a, respectively, each of the bottom panels 26 and 27 being rectangular and of substantially the same width as the associated side panels 15-16, and of a length corresponding to the distance of the apex of the panel 19 from the fold line 20. The panels 26-27 are provided with complementary apertures 28-29, inclusive, and with a slanting score line 30 defining deflectable end portions 26b and 26c, respectively, for a purpose to be hereinafter more fully described. Panel 15 and the associated bottom panel 26 are longitudinally traversed by an additional score line 32 which is intermediate the total combined width of the panels 14, 15 and 16.

As a first step in the assembly of the container, tubular supporting legs 33 are secured to the bottom panel 19. As best shown in Figures 4 and 6, a tubular leg 33 is provided to encircle each of the groups of segmental tabs 21. The assembly of the tubes to the bottom panel is accomplished by first positioning the tubes 23 to overlie the concentric tabs with the inner periphery of the tube substantially coinciding with the score line 25 surrounding the groups of tabs. The tabs 24 are next deformed downwardly into the interior of the tube to abut the inner periphery thereof in extended surface engagement, and the tabs are adhesively secured thereto. A convenient means of adhesively securing the tabs to the tubes is by the prior application of an adhesive to the undersurfaces of the tabs, and then the deformation of the tabs into adhesive contact with the tubes.

Following the securing of the tabs 24 to the inner periphery of the tube 23, a central annular locking ring 34 is inserted into the assembly to abut the inner periphery of the tabs 24 to reinforce the same and to retain them in radially spread relation against the inner periphery of the tube 33. It will be seen from the prior description that an aperture 35 is formed in the triangular bottom wall 19 by the deformation of the tabs 24 downwardly into the interior of the tube 33.

As the next step of the assembly of the container, the side wall 16, together with the bottom flap 27 and top flap 17 associated therewith, and the immediate adjacent portion of the side panel 15, together with the bottom flap 26 and the upper flap 17 associated with this panel, are folded along the score line 32 to overlie the remainder of the panel 15 and the back side panel 14. A strip of adhesive tape or other fastening means 39 is then applied to the adjacent edges of the panel 16 and the panel 14. The sub-assembly, thus including the complete blank with the legs attached thereto, may be shipped in this folded, compact form.

To set up the container, the secured sides are first spread to define the triangular configuration illustrated in Figure 5, and the bottom flaps 26 and 27 are pivoted upwardly and inwardly about their respective score lines 26a and 27a to underlie the triangular shape. The bottom flap end portions defined by the score lines 30 are first folded upwardly, so that they abut the inner surface of the back side panel 14, as best shown in Figure 4.

Following the infolding of the bottom panels 26 and 27, the leg-bearing triangular bottom panel 19 is folded upwardly about its score line 20 to underlie the bottom

flaps 26 and 27. The bottom flaps 19, 26 and 27 are then secured together by suitable means, as by stapling, adhesives, or the like.

The container may then be filled with flowable material, such as that material hereinbefore described, and following the filling, the upper marginal flap 17 may be folded inwardly as in Figure 4 to overlie the margin of the upper ends of the container. Next, a triangularly shaped top 36 is assembled from a suitable blank such as that illustrated in Figure 7. The blank includes the top portion 36 and marginal dependent side flaps 37 provided with reinforcing corner tabs 38 as is well known in the art. The top side flaps 37 telescope downwardly over the open top container, so as to provide a finished closed container.

The container assembly shown in Figures 1 and 2 is obtained by abutting the longer rear side panel 14 of a pair of triangular containers 11 and binding the two containers as a unit by means of reinforcing steel strapping 12 supplied and secured as is known in the art.

It will be seen that upon assembly of the container the apertures defined by that row of segmental tabs 21 adjacent the fold line 20 of the panel 14 will be closed by the overlying bottom flaps 26 and 27. However, the apertures 28 and 29 of the flaps 26 and 27, respectively, will overlie the aperture formed by the downwardly deformed and secured tabs 24 of the set of tabs 21 at the apex of the triangular bottom panel 19. Thus, communication through that leg 33 directly underlying the aperture will be permitted to afford egress for material within the container.

The dispensing orifice thus provided is controlled by a valving element which may suitably take the form of a slideable, generally triangular tray 40 formed of metal or other suitable material which is inserted between the lowermost flap 19 of the container and the superimposed flap 27. The tray 40 is provided with a marginal flange 41 along two sides thereof, the flange abutting the outer surface of the panels 15 and 16 adjacent the lower adjacent portions thereof, as indicated in Figure 4.

A strip of adhesive sealing tape of the like 42 is secured over the flange 41 to retain the tray in position to overlie the leg 33. The binding straps 12 as hereinbefore explained also overlie the flange 41 to aid in retaining the tray in its interposed position despite shifting or shocks imposed on the container assembly.

To dispense flowable material from the container 11, it is only necessary to slide the tray or valving element 40 from its interposed position overlying the aperture 35 so that dispensing may occur through the legs 33. It will be appreciated that if it should be desirable to dispense through more than one leg, registering apertures may be provided in the flaps 26 and 27 to overlie the segment groups 21 with a valving element being provided to control such dispensing.

The advantages residing in applicants' invention are several, and include the provision of supporting legs 33 to raise the bottom of the container for facilitating use of the container by a hand or power truck having lift forks extending between the legs 33 for elevating the container. The multi-thickness bottom wall of the container provides adequate support for the load imposed thereon by material contained therein, and it is thus not necessary to provide separate pallet means for employment with the container. The triangular shape of the container permits the binding of a pair of containers into a compact, easily movable assembly while permitting subdivision of the load carried by the container assembly. The utilization of the leg as a dispensing guide or conduit is also advantageous in truck operation, inasmuch as there is no possibility of the dispensing bosses being covered by the lifting forks themselves to prevent such dispensing. The slideable valving element 40 permits the user to control the dispensing of flowable material as he desires with this material being guided through the hollow supporting leg 33 with obvious advantageous results.

It will be understood that modifications and variations may be effected without departing from the scope of the novel concepts of the present invention.

We claim as our invention:

1. A palletized shipping structure comprising a plurality of upstanding wall panels, bottom closure panels formed integrally with said side wall panels and cooperating to define a multi-thickness bottom closure wall, tubular supporting legs secured to the undersurface of said bottom closure wall, means establishing communication between the interior of at least one of said tubular legs and the interior of said container, and means slidably journaled by said container and interposed between the interior thereof and said legs for controlling said communication.

2. In a shipping container having a plurality of upstanding side walls and a multi-thickness bottom wall defined by lower closure flaps formed integrally with the side walls, tubular supporting legs secured to the lower-most flaps of the bottom wall and communicating with the interior of said container, and a valving element interposed between the bottom closure flaps controlling communication between the interior of at least one of said legs and the interior of said container.

3. In a shipping container, a plurality of upstanding side walls having bottom closure flaps integrally formed therewith, means securing said bottom closure flaps to one another to define a multi-thickness container bottom wall, said flaps having registering apertures formed therein communicating with the interior of said container, a tubular supporting leg registering with said apertures and depending from said bottom wall, and valving means interposed between said flaps for controlling communication of the interior of said container with the interior of said legs through said registering aperture.

4. A palletized shipping container comprising upstanding side walls, bottom closure walls having registering apertures communicating with the interior of said container, hollow tubular legs depending from said bottom walls and having their interior communicating with the interior of said container through said registering apertures, and a valving element interposed between said bottom walls for controlling said communication.

5. A palletized shipping structure comprising upstanding side walls, a multi-thickness bottom wall having registering apertures therethrough, a container cover cooperating with said side walls, and said bottom walls to define an enclosed interior space, a depending supporting leg aligned with said apertures and having an interior bore communicating through said apertures with said interior space, and a slidably valving element journaled by said bottom wall and interposed between said interior space and said leg bore to control communication therethrough.

6. A palletized shipping structure comprising a pair of separable shipping units each of triangular configuration and enclosing an interior space, means binding said containers into a rectangular shipping unit, hollow supporting legs at opposed corners of said units and each communicating with the interior of the associated unit, and valving means for controlling the independent dispensing of material from said interior spaces through said supporting legs, said valving means in each unit being located in the bottom of each unit within the confines of the area of attachment of a leg to the bottom whereby said bottom is reinforced at the location of said valving

means therein, said binding strap serving to retain said valving elements in closed position in shipping of said structure.

7. A palletized shipping structure comprising upstanding side walls, a multi-thickness bottom wall and a cover cooperating to enclose a triangular inner space, supporting legs at the corners of said container, one of said legs having an interior open bore communicating with said enclosed space, and a triangular sliding valve element insertable between said one leg and said space and journaled for sliding movement by said bottom wall for controlling communication of said space through said legs.

8. A palletized shipping structure comprising a rear side panel, front side panels formed integrally with said rear panel and cooperating therewith to define a triangularly-shaped open-ended container having an apex at the juncture of said front panels, means closing the open ends of said container including a multi-thickness bottom having registering apertures at the apex of said front panels, hollow supporting legs secured to said multi-thickness bottom and including one leg in alignment with said registering apertures for communication with the interior of said container, and a slidable valve element journaled by said bottom to underlie the apex of said front panels and interposed between the registering apertures of said bottom panel to thereby control the dispensing of material from the interior of said container through one said hollow leg.

9. In a shipping container for flowable material, a plurality of upstanding side walls and a bottom wall, supporting legs connected to said bottom wall and at least one of which is tubular so that its bore is aligned and defines with an aperture in said bottom wall a discharge spout through which material contents of the container can flow and material flow control means carried by said bottom wall at right angles to the bore of said tubular leg and comprising a closure for the aperture in the bottom wall to afford a barrier to the flow of material through said tubular leg and being exteriorly of the container, manually displaceable to open said aperture for flow of material through said tubular leg.
